UNITED STATES PATENT OFFICE

JOSEPH PANICO, OF WHEELING, WEST VIRGINIA

ROLLING WINDOW SCREEN

Application filed June 25, 1928. Serial No. 287,920.

The present invention has reference to an improved window screen and relates more particularly to the roll type of window screen equipped with novel guide means whereby the screen will effectively prevent the entrance of insects into a room through windows provided with this improved screen construction.

The main objection to the present types of rolled window screens is in their inability to completely prevent the entrance of insects, especially because they do not provide the necessary means for shielding the longitudinal edge portion of the screen strip.

The prime object of this invention is to provide guide means for the screen strip which is employed in lieu of the usual inside sash strips and which also serves as a shield for the longitudinal edge portions of the screen strips to prevent the passage of insects.

Another object of importance resides in the shifting means associated with the screen strip whereby the strip will be prevented from bulging and becoming displaced from the guide members.

Still another object is to provide guide means in the form of members extending vertically at opposed sides of the window frame, and which are adjustable to permit the actual removal of the stiffened end portion of the screen strip from its association with the window.

After reading the following specification and claim, other important objects and advantages of the invention will become apparent.

In the drawings:

Figure 1 represents an inside elevation of a conventional window frame equipped with the present improved window screen.

Figure 2 is a longitudinal sectional view through the window frame and screen construction, and disclosing in side elevation the particular guide means employed in conjunction with the screen strip.

Figure 3 is a fragmentary perspective view of the screen strip and showing the stiffening member associated therewith.

Figure 4 is an enlarged fragmentary sectional view, taken substantially on the line

4-4 of Figure 1, for disclosing the particular construction of the guide member, and

Figure 5 is an enlarged perspective view of a fragmentary portion of one of the guide members with the hinged plate member thereof shown in open position, and

Figure 6 is an enlarged perspective view of the horizontal guide member employed at the top of the window frame for maintaining the screen in a position obstructive to the passage of insects.

Now referring to the drawings, wherein like numerals designate like parts, a window frame of conventional structure is shown in the drawings, and designated by A, in lieu of the usual inner stop strips there being provided a pair of guides 1-1, these guides resting at their lower ends upon the usual sill structure B while terminating at their upper ends at the upper end of the window opening.

These guides are vertically disposed within the window frame and secured to the opposite sides thereof in the manner clearly shown in Figure 1. These guides each consists of an elongated plate 2, secured to the frame and provided with a flange 3 for abutting relation with the inner sash of the window structure. The boss 4 having a threaded bore is located on the plate 2, intermediate its ends and is adapted to receive a wing screw 5.

A plate 6 of elongated extent is of angular shape in cross section as is shown in Figure 4.

This plate 6 has one longitudinal edge portion thereof substantially arcuate in cross section as designated by numeral 7. The longitudinal edge of the arcuate portion 7 of the plate 6 is hingedly connected to the outer longitudinal edge of the plate 2, by a suitable hinge construction 8. The opposite longitudinal edge of the plate 6 is preferably beaded or rolled as at 9, while the plate 6 is formed slightly inwardly from this edge with a relatively short longitudinally extending slot 10. This slot 10 permits the projection of the wing head of the screw 5 through the plate 6, so that by turning the screw 5, the plate 6 may be secured to the

plate 2, in the relation shown clearly in Figure 4. It is also to be noted that the rolled or beaded edge of the plate 6 is closely spaced from the adjacent longitudinal edge of the flange 3, so as to permit the free sliding motion of the screen strip, which will be fully described hereinafter. The upper portion of each guide 1 is preferably disposed outwardly as at 11, while the guide strip 12 is secured to the underside of the usual horizontal portion C of the window frame, overlying this outwardly disposed portion of the guide, in the manner shown in Figure 2. This guide strip 12 is formed with a longitudinally extending slot 13, the portion of the strip struck to form the slot 13 being bent downwardly to provide a rib 14 against which the screen strip is adapted to bear.

20. Mounted for rotation on suitable brackets at the top of the window frame A is the conventional spring roll D on which the screen strip 15 is to be wound.

25. A substantially U-shaped stiffening member 16 is secured to the end portion of the screen strip 15 in the manner clearly shown in Figure 3. The bight portion of this stiffening member is secured to the end edge of the strip, whereas the leg portions of the member are secured along the longitudinal edges of the strip for a substantial distance approximately ascertainable by the dotted line illustration in Figure 1. The bight portion of the U-shaped member 16 is formed 30 at its intermediate portion with an outwardly disposed and curved loop 17, which is adapted for engagement by the hand of a person in lifting the screen strip 15.

35. The leg portions of the stiffening member 16 as well as the longitudinal edge portions of the screen strip 15 is adapted to ride within the guides 1-1. The leg portions of the stiffening member 16 are substantially greater in diameter than is the space between the edge 9 of the plate 6 and the flange 3 of the plate 2 in the guide constructions, so that the shifting and disengagement of the screen strip 15 from its connection with the said guides is prevented.

40. Obviously, should it be desired to remove the screen strip 15 from the window, the wing screws 3 may be rotated to register with the slot 10, whereby the plates 6 may be swung outwardly to permit the displacement of the screen strip.

45. It is also to be understood that certain changes in the shape, size or materials may be resorted to, without departing from the spirit of the invention or the scope of the appended claim.

Having described the invention, what is claimed as new is:

50. In a window screen of the character described having an elongated foraminous strip of material; guide means at the op-

posite sides of the window frame, the longitudinal edges of said strip being engaged in said guide members, means for disengaging the strip from said guide means, said guide means at each side of the frame consisting in construction of an elongated plate secured to the frame, an elongated plate hingedly connected to the fixed plate, certain adjacent longitudinal edges of said plates being disposed in spaced relation to permit the 55 slideable movement of the screen strip therebetween, said hinged plates formed with a slot, a winged screw threadedly engaged in the fixed plate and disposable through said slot and adapted to be turned transversely to said slot for securing the hinged plate in definite spaced relation with respect to the fixed plate.

In testimony whereof I affix my signature.

JOSEPH PANICO.
